UNITED STATES PATENT OFFICE

SAMUEL H. TURNER, OF METROPOLIS, ILLINOIS.

DESIGN FOR A BED-SPRING.

SPECIFICATION forming part of Design No. 13,820, dated March 27, 1883.

Application filed February 9, 1883. Term of patent 7 years.

To all whom it may concern:

Be it known that I, SAMUEL H. TURNER, a citizen of the United States, residing at Metropolis, in the county of Massac and State of Illinois, have invented certain new and useful Improvements in Bed-Springs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a new and original design for bed-springs of the class known as "twin springs."

In the drawings, Figure 1 represents a plan view of my design, and Fig. 2 represents a modified form of the same.

A A represent the two coiled sections of the spring, the upper coils, B B, of which are bent to the form of a horseshoe.

C represents the wire for connecting the two coils, said wire being bent to form two opposite loops, D D, of horseshoe form. In Fig. 2 these loops D D are omitted.

It will be apparent that the spring as thus constructed will be neat, unique, and finished in its appearance.

I claim—

1. A design for twin bed-springs, consisting of horseshoe-bends formed by the upper coils of the springs, substantially as set forth.

2. A design for twin bed-springs, consisting of the upper coils of the springs bent into horseshoe form, and a connecting-wire for the springs bent to form opposite horseshoe-loops, substantially as set forth.

In testimony whereof I affix my signature in presence of two witnesses.

SAMUEL H. TURNER.
